UNITED STATES PATENT OFFICE.

CARL SCHLIMP, OF VIENNA, AUSTRIA-HUNGARY, AND RUDOLF CHAROUZEK,
OF NIEDERSEDLITZ, NEAR DRESDEN, GERMANY.

HYDRAULIC PRESS.

SPECIFICATION forming part of Letters Patent No. 573,710, dated December 22, 1896.

Application filed August 17, 1896. Serial No. 603,052. (No model.)

To all whom it may concern:

Be it known that we, CARL SCHLIMP, a resident of Vienna, Austria-Hungary, and RUDOLF CHAROUZEK, a resident of Niedersedlitz, near Dresden, Germany, subjects of the Emperor of Austria-Hungary, have invented certain new and useful Improvements in Hydraulic Presses, of which the following is a specification.

10 Our invention relates to hydraulic presses for dry materials, its object being to improve and to simplify its operation.

In the accompanying drawings, Figure 1 represents a fragmentary view of the improved press, with parts shown in section. Fig. 2 is a plan showing diagrammatically the arrangement of valves and pipe connections and accessory parts. Fig. 3 is a vertical section of the delivery-press. Figs. 4 and 20 5 are sections on the lines E F and G H, Fig. 2, respectively. Fig. 6 is a diagram showing the pipe connections.

I is the first or preliminary hydraulic press. II is the main press, and III is the delivery-press. X is the intermittently-revolving platform with the equidistant forms or molds XI. The presses I II III are arranged the same distance apart as the forms or molds, so that when one mold is under the press I another 30 mold is under the main press and a third mold is under the delivery-press III.

The first press is provided with a main plunger a and with a small plunger b in the upper cross-head. This small plunger serves 35 to raise the forms or molds up to the upper cross-head by means of a plate c and hooked rods d, thereby closing the top of the mold. The bottom of the upper cross-head of the delivery-press III is provided with stops e, 40 coming against and stopping the mold while the pressed material is forced out of the mold by means of the plunger f and the plunger head, Fig. 3.

The water-tubes from the low-pressure accumulator V and the high-pressure accumulator VI lead to a valve-box VIII, the admission of the water under pressure and the escape of the water being controlled therein by valve-levers h and i. From the valve-box 50 VIII the connecting-tubes lead to the various presses. The accumulators V and VI are

loaded to correspond to the requisite pressures.

For the sake of clearness, in the drawings the valve-box VIII is shown separated in 55 Fig. 6.

The operation of the valves in the box VIII is as follows: By raising the lever h the valve k is opened, while valve l is closed and low-pressure water is admitted to the various 60 presses. When, however, the lever h is at rest, as shown in Fig. 4, the valve k is closed and the valve l is open, and the water is allowed to escape from the various presses to the pump IV by the escape-pipes. (Indicated 65 by full lines.) When the lever i is raised, high-pressure water is admitted to the main press II, and escapes, after having done its work, together with the other escape-water, into the escape-pipes.

70 The mechanism for imparting an intermittent revolving motion to the platform X consists of two hydraulic cylinders m n, having a common plunger o, provided with a projecting cross-bar p, engaging at one end with a 75 slide q and at the other into a slotted arm r, pivoted at the center of the circular platform X. The lever r co-operates with teeth s of the circular platform X. The slide q is provided with a roller acting against an incline 80 on the lever i of the valve-casing VIII when the plunger o moves from the cylinder m to the cylinder n. The lever h is acted upon by a plunger t and is raised thereby when water under pressure is admitted under such plunger.

75 The fluid may be exhausted from the cylinder m when liquid-pressure is admitted into cylinder n, and vice versa, in the following way: The cylinders m and n are provided 90 with the valves y and y', respectively, and attached to the piston-rod o are two valve-rods x and x', having projections z z' and z'' and z''' respectively. Between these projections the rods engage the arms of the valves, 95 so that when pressure is admitted to n, the valve y' being closed and the valve y open, the rod o moves to the left in Fig. 6, and when about at the end of the stroke the projection z' on rod x closes valve y and projection z''' on rod x' opens valve y', and when the rod o 100 starts on its backward stroke and reaches the

end of that stroke the opening and closing of the valves is reversed, that is, valve γ is opened and γ' closed. It is obvious, however, that any simple and efficient means may be employed for exhausting fluid from the cylinders.

The valve-box IX, from which the action of the whole press is controlled, receives its water under pressure from the accumulator VII, which is connected to this valve-box only, while the accumulators V and VI furnish water under pressure to the various presses.

In Fig. 2 of the drawings the pipe connections are indicated by lines of different character for the sake of clearness, the pipes themselves being shown in Fig. 6. The pipes from the low-pressure accumulator V are indicated by dotted lines, the pipes from the high-pressure accumulator VI are indicated by dot-and-dash lines, those from the accumulator VII by dash-lines, and the escape-pipes are indicated by full lines. The accumulators receive their water from the pump IV.

The operation of the press is as follows: Let the valve u of the valve-box IX be opened, as shown in Figs. 2 and 6. The water from the accumulator VII flows through the box IX to the cylinder n and drives the plunger o into the cylinder m . The bolt p moves the lever r , which, by acting against the tooth s , moves the platform X, together with the molds XI upon the same, through the distance between two adjacent molds. Now when the valve v of the valve-box IX is opened the water from the accumulator VII enters below the plunger b in the upper cross-head of the first press I. At the same time water under pressure enters below the plunger t and behind the plunger o into the cylinder m . By these means, first, the mold is raised against the upper cross-head of the first press I and is thereby closed; secondly, the lever h is raised by the plunger t , and, thirdly, the plunger o is moved back into the cylinder n . By lifting the lever h water under pressure is admitted from the accumulator V to the cylinder of the press I and also to the cylinder of the main press for the first part of the main pressing, and further to the cylinder of the delivery-press III, where the material already pressed is pushed out from the mold. After the plunger o has moved from the starting-point for a certain distance the slide q raises the lever i by coming into contact with its incline, as shown in Figs. 5 and 6, and thereby admits high-pressure water from the accumulator VI into the press II. The pressing is thus completed. At the same time the arm r is brought back into the normal position. The parts are then ready for a new operation.

Instead of controlling the valve-box VIII, the valves k l , and the plungers m and n by the valve-gear IX they may be controlled by separate mechanisms.

We claim—

1. The combination with a revolving plat-

form, of molds carried by said platform, a hydraulic press having a supplementary chamber and plunger for raising and closing said molds and a main chamber and plunger for compressing said molds, a second hydraulic press adapted to further compress said molds, a third hydraulic press adapted to deliver said molds from said platform, a series of accumulators, pipes connecting said accumulators with said presses, valves for controlling the flow of the fluid in said pipes, and means for rotating said platform through fixed distances, substantially as described.

2. The combination with a revolving platform, of molds carried by said platform, a hydraulic press having a supplementary chamber and plunger for raising said molds and a main chamber and plunger for compressing said molds, a second hydraulic press adapted to further compress said molds, a third hydraulic press adapted to deliver said molds from said platform, a series of accumulators, pipes connecting said accumulators with said presses, valves for controlling the flow of the fluid in said pipes, a pair of cylinders having reciprocating pistons, a rod connecting the said pistons, a pivoted arm connected to said rod, a plurality of projections on said platform adapted to engage said pivoted arm and pipes connecting said cylinders with the aforesaid valves and accumulators, substantially as described.

3. In a system of hydraulic presses, the combination with a revolving platform, of molds carried by the said platform, a hydraulic press having a supplementary chamber and plunger with arms for raising and closing the said molds and a main chamber and plunger for compressing said molds, a second hydraulic press for further compressing said molds, a third hydraulic press adapted to deliver said molds from said platform, a series of accumulators, pipes connecting said accumulators with said presses, valves for controlling the flow of the fluid in said pipes, a pair of cylinders having reciprocating pistons, a rod connecting said pistons, a pivoted arm connected to said rod, a plurality of projections on the said platform adapted to engage said pivoted arm, a second arm connected to said piston-rod, a valve adapted to be opened by said arm, high-pressure pipes connecting said valve with said second press, and pipes and valves connecting said cylinders with said accumulators, substantially as described.

4. In a system of hydraulic presses, the combination with a circular revolving platform, of molds carried by the said platform, a hydraulic press having a supplementary chamber and plunger with arms for raising and closing the molds and a main chamber and plunger for compressing the said molds, a second hydraulic press for further compressing said molds, a third hydraulic press adapted to deliver said molds from said platform, a series of accumulators containing a fluid at different stages of compression, pipes con-

necting the low-pressure accumulator with all of the presses, a valve for controlling the flow of low-pressure fluid into said presses, a pipe connecting the high-pressure accumulator with the second hydraulic press, a valve for controlling the flow of high-pressure fluid in said pipe, means for simultaneously revolving said platform through fixed distances and operating the said high-pressure-controlling valve and a valve for simultaneously controlling the operation of said means and all of said controlling-valves, and a pump connected with the exhaust from said presses and

adapted to pump fluid under pressure into said accumulators, substantially as described. 15

In testimony whereof we have affixed our signatures in presence of two witnesses.
